COLLAPSIBLE TRESTLE

Charles L. Edwards, St. Louis, Mo.

Application November 27, 1936, Serial No. 112,908
Renewed April 7, 1938

4 Claims. (Cl. 304—5)

This invention relates to certain new and useful improvements in collapsible trestles, the peculiarities of which will be hereinafter fully described and claimed.

More specifically my improvements relate mainly to connecting corner brackets on supporting legs, each pair of said brackets having transverse arms pivoted together and longitudinal arms engaging the side edges of a longitudinal 5 plank connecting opposite pairs of corner brackets on their supporting legs.

The main objects of my invention are to provide means first, for securely engaging each end of a horizontal connecting plank with the adjacent 15 pair of supporting legs; and second, for a trestle that is strong, adapted for use by masons, carpenters and others, is practically indestructible in ordinary circumstances, and can be readily taken apart, occupies small space in transportation, and 20 can be quickly set up for use.

In the accompanying drawing in which like reference numerals indicate corresponding parts:

Fig. 1 represents a side elevation of a trestle embodying my invention;

Fig. 1a, an enlarged detail on the section line 1a—1a, Fig. 1.

Fig. 2, an end view of Fig. 1;

Fig. 3, an enlarged detail in isometric projection of a pair of supporting legs and their connecting corner brackets;

Fig. 4, a face view of a corner bracket as stamped from metal plate in its flat condition before bending at right angles on the dotted lines; and

Fig. 5, a vertical edge view of the same in said flat condition.

Referring to the drawing, the numerals 1—1' designate a pair of supporting legs of angle iron or other suitable shape, disposed substantially vertical in a transverse plane and slightly inclined 40 in longitudinal planes as desired. On the top end of these legs is securely mounted by rivets or otherwise, corner brackets consisting of flat plate arms 2 and 3, at right angles to each other in transverse and longitudinal position respectively, 45 from the meeting corner 4. The longitudinal arm is preferably at a higher level than the transverse arm to allow the longitudinal connecting plank 5 to project as shown in Fig. 1, as is usual in such trestles; but they may be otherwise disposed. Although in different horizontal planes, both these arms have definite downward extensions 6—7 in planes meeting at right angles on said corner 4 to form a downward angle extension of said arms that corresponds to the angle 50 leg that is secured thereto by rivets or other-

wise. The brackets are thus rigidly secured to their respective legs. Their matching transverse arms 2—2' are pivotally connected by a removable bolt 8. Spaced holes in said transverse arms allow of varying the transverse distance between 5 the longitudinal arms 3—3' of the brackets so as to receive planks of different width. A wide plank may thus be used as a bench by a carpenter or plumber.

This corner bracket is preferably made from 10 rolled plate metal (Fig. 5) that can be cut to the desired shape and the holes punched by stamping dies; then bent at right angles to the dotted line Fig. 4, to right or left, to form the right or left bracket shown in Fig. 3.

In its flat shape shown in Figs. 4 and 5, the two arms 2 and 3, point in opposite directions in the same plane but unaligned with each other, and are connected by an integral lateral extension from the inner ends of said arms, which extension is common to both the arms. The portions of said extension on opposite sides of a medial dotted line, form flanges 6 and 7 of a right angle extension when the flat shape is bent on this line so as to adapt the bracket for fastening to the respective supporting leg angles 1—1' as shown in Fig. 2. The arms 2 and 3 respectively integral with the flanges 6 and 7, are thus disposed in planes at right angles to each other, the arm 2 being adapted for pivotal connection 20 with the corresponding transverse arm 2' of the opposite bracket as previously described, and the arm 3 being disposed longitudinal to the trestle and adapted for supporting the plank interposed 25 between arms 3—3'.

The bracket may be otherwise made, but investigation indicates the stated method as being 30 cheaper and preferable for production in quality.

The horizontal arm 3 is flat like the pivoted arm 2, and angle extensions 9—9' are riveted or 40 otherwise secured to the respective arms 3—3' which are disposed parallel and opposite each other, so that their horizontal flanges support said interposed plank 5, while the vertical flanges, slightly inclined inward (Figs. 2 and 3) grip the 45 side edges of the plank. Such gripping engagement is supplemented by pointed rivets 10 (Fig. 3) having shoulders fitting against the inner face of said vertical flanges and the reduced shank extending through the flange and adjacent 50 arm and headed on the outside in the usual manner. Thus two or more pointed rivets in each of the arms 3—3' secure the extensions 9—9' rigidly to the arms and also provide positive engaging means for the plank.

Swinging the legs 1—1' on the pivot bolt 8 toward each other, will widen the space between the angle extensions 9—9' for placing the plank between them. Then, spreading said legs will force the points 10 into positive engagement with the plank. The legs are thus braced outward by a spreader bar 11, pivoted to one leg and having notches near the other end, one of which engages a stud pin 12 in the opposite leg, as shown in Fig. 2. A similar notched bar 11' near the remote ends of the extensions 9—9' also serves as a connector to hold the adjacent points 10 engaged with the plank after they have been forced into it by hammer blows or otherwise.

Fig. 1a shows this bar 11' engaged with the stud pin 12' in the horizontal flange of the adjacent angle extension.

Fig. 3 shows the preferred construction having the upper faces of the horizontal flange of the angle extensions 9—9', and the adjacent top of the lower plate arms 2—2', disposed substantially in the same plane so as to be even with each other and thus contact with the bottom of the inserted plank so that both assist in supporting it.

The legs may be lengthened as indicated in Fig. 1, by bolting an angle or other piece to said legs. In using such a trestle on a sloping roof for instance, one of the legs of each pair is lengthened, as much as required by the slope.

A diagonal brace 13 from the end of an angle extension down to the adjacent leg (Fig. 1) may be used when the legs are of such length that stiffening them, or the middle of the plank, is desirable.

When collapsing the trestle, the spreader bar 11 and connector bar 11' are disengaged from their stud pins, and the pivot bolt 8 removed in each pair, so that the dismantled members take up comparatively little room in transportation or storage.

Having thus fully described my invention what I claim as new and desire to secure by Letters Patent, is:

1. A collapsible trestle having in combination, a vertically disposed angle iron leg, a horizontal angle iron support for a plank, and a connecting

corner bracket consisting of a flat rolled plate having arms bent at right angles to each other, one arm being above the other arm and riveted to the vertical flange of said angle support so that the horizontal flange of said support is even with the lower arm of the said bracket, and said lower arm having spaced holes for variably pivoting to a matching arm of an opposite bracket, and a downward angle extension from said arms riveted to said angle leg whereby said leg and horizontal angle support are rigidly connected substantially as described. 5

2. A collapsible trestle having in combination, horizontal parallel opposing angle supports for an inserted plank, means for pivotally adjusting the space between said supports to grip the inserted plank, and a notched bar pivoted under the end of one support and having notches near its other end variably engaging a stud pin projecting below the opposite support to tie the ends of said supports in gripping position, substantially as described. 10

3. In a collapsible trestle the herein described pair of corner brackets having arms respectively pivoted together disposed transversely to the trestle, and each bracket characterized by an arm at right angles to and higher up than, its transverse arm and adapted to support an interposed plank, and both arms of respective brackets having downward extensions forming flanges in 20 planes meeting at right-angles on a corner and adapted to be secured to respective supporting legs, substantially as described. 25

4. In a collapsible trestle the herein described pair of corner brackets having flat metal plate 35 arms with spaced holes for adjustably pivoting together transversely to the trestle and each bracket characterized by a plank-supporting arm at right angles to and higher up than its transverse arm, and both arms of respective brackets 40 having integral downward extensions forming flanges at right angles to each other in planes meeting on a corner and adapted to be secured to respective supporting legs, substantially as described. 45

CHARLES L. EDWARDS.
